TOILET CONVENIENCE FOR AUTOMOBILES

Original Filed Oct. 20, 1924

FIG. 1.

FIG. 2.

Inventor.

by F. J. Pew, Inventor and Assignor.

UNITED STATES PATENT OFFICE.

FRANKLIN JONES PEW, OF ST. CATHARINES, ONTARIO, CANADA.

TOILET CONVENIENCE FOR AUTOMOBILES.

Application filed October 20, 1924, Serial No. 744,828. Renewed August 8, 1925.

To all whom it may concern:

Be it known that I, FRANKLIN JONES PEW, a subject of the King of Great Britain, and a resident of the city of St. Catharines, in the county of Lincoln, in the Province of Ontario, Canada, have invented certain new and useful Improvements in Toilet Conveniences for Automobiles, of which the following is the specification.

10 My invention relates to improvements in toilet conveniences for automobiles and the object of the invention is to devise a normally concealed toilet seat which on the temporary removal of one of the car seats 15 can be turned down so as to be positioned above an opening in the floor of the car.

A further object is to devise a door for normally closing the orifice in the floor of the car which can be turned up to support the forward edge of the toilet seat.

20 My invention consists of a toilet convenience constructed and arranged all as hereinafter more particularly described and illustrated in the accompanying drawing in 25 which:

Fig. 1 represents a vertical cross section through a portion of the body of the car showing the seat of my toilet in the turned down position in full lines, and showing it 30 swung up into the concealed position in dotted lines.

Fig. 2 is an elevational view taken at right angles to Figure 1.

Like characters of reference indicate corresponding parts in the different views.

1 is the floor of the car provided with a seat base 2 upon which the car seat 3 is removably mounted, said base 2 having a rectangular orifice 12 extending therethrough, 35 normally closed by the double hinged doors 4. 5 is my toilet seat which is adapted to be hinged to the side of the car and to be capable of being swung into the recess 6 so as to assume the position indicated in dotted lines in Figure 1. 7 are spaced apart battens positioned in the vicinity of the forward edge of the bottom of the seat 5 and the

free edge of the inner door 4 is inserted therebetween as indicated in Figure 1, thus supporting the seat 5 in position.

50 8 is the flap of upholstery adapted to extend down over the recess 6 when the seat 5 has been folded up into the inoperative position.

To use the device the seat 3 is removed 55 from the base 2 and the upholstery flap 8 turned up out of the way. The seat 5 is now swung down and the doors 4 turned upwardly.

The rear door 4 lies against the side of the 60 car, the upper edge of the forward door 4 being inserted between the battens 7.

9 are curtains of flexible material adapted to depend from the sides of the seat 5 and to close the space between the sides of the 65 seat 5 and the base 2.

From the above description it will be seen that I have devised a simple and effective 70 toilet convenience for use in automobiles which when not required will be concealed from view and which can be turned into position ready for use with the minimum of trouble.

What I claim as my invention is:

1. In an automobile body, the combination 75 with the floor and one side wall, of a toilet seat hinged to the side wall and adapted to be swung down over an orifice in the floor, double hinged doors normally closing the orifice in the floor, the free edge of one upturned door supporting the turned down toilet seat.

2. In an automobile body, the combination with the floor and one side wall, of a 80 toilet seat hinged to the side wall and adapted to be swung down over an orifice in the floor, double hinged doors normally closing the orifice in the floor, spaced apart battens secured to the underneath face of the 85 toilet seat in the vicinity of its forward edge, the free edge of one upturned door inserted between the battens.

FRANKLIN JONES PEW.
